[57] CLAIM

The ornamental design for a housing for a gas fired
barbeque, as shown and described.

DESCRIPTION

FIG. 1 is a perspective view of a housing for a gas fired
barbeque showing my new design;

FIG. 2 is an end elevational view thereof;

FIG. 3 is an end elevational view thereof, of the oppo-
site side of FIG. 2;

FIG. 4 is a front elevational view thereof;

FIG. 5 is a rear elevational view thereof;

FIG. 6 is a top plan view thereof;

FIG. 7 is a bottom plan view thereof.

FIG. 5FIG. 6FIG. 7
